UNITED STATES PATENT OFFICE.

ARTHUR WILZIN, OF CLICHY, FRANCE, ASSIGNOR TO E. W. BLISS COMPANY, A CORPORATION OF WEST VIRGINIA.

FEEDING MECHANISM FOR PUNCHING AND LIKE MACHINES.

No. 836,424.

Specification of Letters Patent. Patented Nov. 20, 1906.

Application filed January 13, 1905. Serial No. 240,861.

To all whom it may concern:

Be it known that I, ARTHUR WILZIN, a citizen of the United States, residing at present in Clichy, Seine, France, have invented 5 certain new and useful Improvements in Feeding Mechanism for Punching and Like Machines, of which the following is a specification.

This invention relates to an automatically- 10 operating and continuously-operated feed device adapted to advance a sheet of metal or other material to a tool of any kind at points arranged in quincunx order. This feeding device is so arranged as to be able to 15 give such a result by means of a very simple and easily-adjustable mechanism.

This device comprises, as all the other machines of this kind, a carriage to which the sheet is secured and which is capable of being 20 moved along a slide parallel to the front of the machine and movable upon a stationary guiding device directed toward the tool. The movement is controlled by a mechanism operated in a continuous manner and combined 25 so as to impart to the carriage along its slide intermittent movements the amplitude of which is equal to the distance which must exist between the centers of the parts of the sheet which are to be acted upon by the tool 30 and to cause at each end of the stroke of the carriage an advance motion of the movable guide toward the tool to take place and a reversal in the direction of motion of the carriage.

35 This feeding device is represented by way of example in the accompanying drawings, in which—

Figure 1 is a cross-section made according to line A A of Fig. 2. Fig. 2 is a plan. Fig. 40 3 is a section made according to line B B of Fig. 2.

This feeding device comprises a carriage *a*, carrying one or several grippers *a'*, in which the sheet which is to be advanced toward the 45 tool is secured. This carriage *a* is capable of being moved longitudinally upon a guide *b*, secured to the carriers *b'*, which can slide transversely on dovetailed slides *c*, with which the frame of the machine is provided.

50 The intermittent movements of the carriage *a* and guide *b* are respectively produced by the crank *d* and wheel *e*. The crank *d* is keyed on the main shaft *f* and the wheel *e* is keyed on the shaft *g*, which receives motion

from shaft *f* through the gear-wheels *g'* *g²* *g³* 55 *g⁴*. The crank *d* and wheel *e* thus both receive continuous rotary motion, each at its own appropriate speed. The crank *d* transmits an intermittent movement to the carriage *a* along the guide *b* with the aid of the Geneva movement shown. At each revolution the crank-pin of crank *d* engages in one of the grooves of the radially-grooved wheel *h* and rotates the latter one-fourth of a revolution. 60

The wheel *h* of the Geneva movement, which is loose upon the shaft *j*, is formed in one with a bevel-pinion *h'*, whose movement is transmitted by the intermediate bevel-pinion *h²* to a bevel-pinion *h³*, which is also 70 loose on shaft *j*. A clutch *j'*, which is capable of sliding longitudinally of said shaft *j*, but turning therewith, is inserted between the pinions *h'* *h³*, so as to be capable of engaging in the one or the other in such manner as 75 to transmit rotary motion in one direction or the other from the wheel *h*, according as the clutch *j'* is thrown into engagement with the pinion *h'* or *h³*. This reversal of the movement, which is necessary on the completion of 80 each longitudinal movement of the carriage *a*, is produced by a cam *k*, keyed on shaft *g*, said cam acting on a lever *k'*, movable about a fixed center *k'* on the machine-frame, to the 85 extremity of which lever the clutch *j'* is attached. The intermittent rotary motion thus imparted to the shaft *j* either in the same direction as that of the wheel *h* or inversely thereto is transmitted by means of 90 the toothed gearing *j²* *l* *l'* *m* to the intermediate shaft *m'*, upon which is splined the wheel *m²*, which gears with the rack *i*. The rack *i* is capable of being shifted longitudinally upon the carriage *a* to an extent equal 95 to half the distance between two successive punchings, so that at each change in the direction of movement the carriage *a* will be moved during one-half only of the movement imparted to the rack *i*, the extent of this lost motion or clearance being regulated by the 100 set-screws *i'* *i²*. The wheel *m²* is journaled in a bracket depending from the guide *b*, so as to partake of the transverse movements of said guide.

105 The arms of the wheel *h* are each formed with a concavity upon their periphery, and a circular cam *n* is keyed upon the main shaft *f* opposite the wheel *h*, so as to engage in the

concavity in the adjacent arm of said wheel immediately the crank-pin of crank *d* escapes from the groove in the wheel *h*, so as to completely arrest the movement of the train 5 of wheels which operate the carriage *a* until the crank *d* engages in the next groove in the wheel for imparting a fresh movement to said carriage *a*. The guide *b*, upon which carriage *a* slides, itself receives at each termination 10 of the course of the latter a transverse movement equal to the distance between the lines of punchings. This movement is imparted to it by the wheel *e*, provided upon its periphery with worm-teeth *e'*, gearing at 15 each revolution with a toothed wheel *o* and imparting to the latter an angular displacement the amplitude of which corresponds to the number and inclination of the teeth *e'*. At the termination of this angular displacement 20 the wheel *o* is provided with recesses *w'*, in which the rim *e²* of wheel *e* enters in order to lock this wheel *o* and the guide *b*. As shown, the teeth *e'* rotate the wheel *o* through a quarter of a revolution, and the rim *e²* then 25 enters a notch between successive quadrants of the wheel *o* and runs in said notch until the wheel *e* makes another complete revolution.

The wheel *e* transmits its motion through 30 a clutch of any kind—such, for example, as the clutch *p*, provided with grippers—to a shaft *q*, turning in two bearings supported from the frame of the machine, which clutch allows the shaft *q* to be freed from the wheel 35 *o* when it is desired to return the carriers *b'*, and consequently the guide *b*, to the original position. The shaft *q* carries at its ends two pinions *q'*, respectively, gearing with two racks secured to the carriers *b'*, upon which 40 the guide *b* is mounted. The ratio of the gears transmitting the motion from shaft *f* to shaft *g* is so devised as to cause the teeth *e'* to mesh with the wheel *o* when the carriage has reached the end of its stroke upon the guide 45 *b*. When this guide *b* has come itself to the end of its stroke, its return to its original position is controlled by any suitable mechanical operating device.

The invention is not restricted to the 50 above-described device. I reserve for myself the right to establish the clearance between the carriage and its feeding device by any mechanical means suitable for that purpose.

This feeding device can be adapted to all 55 kinds of cutting, stamping, embossing, punching, and printing machines and the like.

I claim as my invention—

1. A feeding device adapted to advance a 60 sheet to the action of a tool at points arranged in quincunx order, comprising a carriage for the sheet, a movable guiding-bar upon which the carriage can be moved longitudinally, a stationary guide perpendicular to this guiding-bar and upon which the latter

can be moved transversely, mechanism communicating successive intermittent longitudinal displacements to the carriage and connected to the latter with a lost motion equal to a fraction of the amplitude of each normal displacement, so that the first displacement is less than normal, and mechanism communicating to the guiding-bar a displacement toward the tool at each termination of the stroke of the carriage, and a driving-shaft to which a continuous rotary motion is imparted and operating the several feeding parts synchronously.

2. A feeding device adapted to advance a sheet to the action of a tool at points arranged in quincunx order, comprising a carriage for the sheet, a movable guiding-bar upon which the carriage can be moved longitudinally, a stationary guide perpendicular to this guiding-bar and upon which the latter can be moved transversely, mechanism communicating successive intermittent longitudinal displacements to the carriage and connected to the latter with a lost motion equal to a fraction of the amplitude of each normal displacement, so that the first displacement is less than normal, means for automatically reversing the motion of the carriage at the end of its stroke along the guiding-bar, and mechanism communicating to the guiding-bar a displacement toward the tool at each termination of the stroke of the carriage, and a driving-shaft to which a continuous rotary motion is imparted and operating the several feeding parts synchronously.

3. A feeding device adapted to advance a sheet to the action of a tool at points arranged in quincunx order, comprising a carriage for the sheet, a movable guiding-bar upon which the carriage can be moved longitudinally, a stationary guide perpendicular to this guiding-bar and upon which the latter can be moved transversely, mechanism communicating successive intermittent longitudinal displacements to the carriage and connected to the latter with a lost motion equal to half the amplitude of each normal displacement, so that the first displacement is one-half the normal, mechanism communicating to the guiding-bar a displacement toward the tool at each termination of the stroke of the carriage, and a driving-shaft to which a continuous rotary motion is imparted and operating the several feeding parts synchronously.

4. A feeding device adapted to advance a sheet toward the action of a tool at points arranged in quincunx order, comprising a carriage for the sheet, a movable guiding-bar on which the carriage can be moved longitudinally, a stationary guide perpendicular to this guiding-bar and on which the latter can be displaced transversely, a feeding-rack mounted upon the carriage with a lost motion in the longitudinal direction, mechanism communicating successive intermittent dis-

placements to this rack, means for reversing the direction of movement of this rack, a device communicating to the guiding-bar a displacement toward the tool at each termination of the stroke of the carriage, and a driving-shaft to which a continuous rotary motion is imparted and operating the several feeding parts synchronously.

5 5. A feeding device adapted to advance a sheet toward the action of a tool of any kind at points arranged in quincunx order, comprising a carriage for the sheet, a movable guiding-bar on which the carriage can be moved longitudinally, a stationary guide perpendicular to this guiding-bar and on which the latter can be displaced transversely, a feeding-rack mounted upon the carriage with a lost motion in the longitudinal direction, adjustable-abutting screws carried from the 10 carriage in front of the two ends of this rack, mechanism communicating intermittent displacement to this rack, means for reversing the direction of movement of this rack, a device communicating to the guiding-bar a displacement toward the tool at each termination of the stroke of the carriage, and a driving-shaft to which a continuous rotary motion is imparted and operating the several feeding parts synchronously.

30 6. A feeding device adapted to advance a sheet toward the action of a tool at points arranged in quincunx order, comprising a carriage for the sheet, a movable guiding-bar upon which the carriage can be moved longitudinally, a stationary guide perpendicular to this guiding-bar and upon which the latter can be displaced transversely, a feeding-rack mounted upon the carriage with a lost motion in the longitudinal direction, a driving-shaft receiving a continuous rotary movement, a crank keyed upon this shaft, a wheel *h* operated by this crank, a train of gearing transmitting the motion from this wheel to the feeding-rack, a reversing device interposed between the wheel *h* and the train of gearing, and a device communicating to the guiding-bar at each termination of the stroke of the carriage a displacement toward the tool.

50 7. A feeding device adapted to advance a sheet toward the action of a tool at points arranged in quincunx order, comprising a carriage for the sheet, a movable guiding-bar upon which the carriage can be moved longitudinally, a stationary guide perpendicular to this guiding-bar and upon which the latter can be displaced transversely, a feeding-rack mounted upon the carriage with a lost motion in the longitudinal direction, a driving-

shaft receiving a continuous rotary movement, a crank keyed upon this shaft, a wheel *h* operated by this crank and whose branches have a concave edge, a circular cam keyed upon the driving-shaft entering at each revolution into this concave edge and thereby 60 steadyng the wheel *h*, a train of gearing transmitting the motion from this wheel *h* to the feeding-rack, a reversing device interposed between the wheel *h* and this train of gearing, a cam operating said reversing device at each end of the stroke of the carriage, an intermediate shaft operated by the driving-shaft and upon which said cam is keyed, and a device communicating to the guiding-bar at each termination of the stroke of the 65 carriage a displacement toward the tool.

8. A feeding device adapted to advance a sheet toward the action of a tool at points arranged in quincunx order, comprising a carriage for the sheet, a movable guiding-bar 80 upon which the carriage can be moved longitudinally, a stationary guide perpendicular to this guiding-bar and upon which the latter can be displaced transversely, a feeding-rack mounted upon the carriage with a lost motion in the longitudinal direction, a driving-shaft receiving a continuous rotary movement, a crank keyed upon this shaft, a wheel *h* operated by this crank and whose branches have a concave edge, a circular cam keyed 85 upon the driving-shaft entering at each revolution into this concave edge and thereby steadyng the wheel *h*, a train of gearing transmitting the motion from this wheel *h* to the feeding-rack, a reversing device interposed between the wheel *h* and this train of gearing, a cam operating said reversing device at each end of the stroke of the carriage, an intermediate shaft operated by the driving-shaft and upon which said cam is keyed, 90 a pinion having transverse recesses, a wheel provided on a small portion of its periphery with worm-teeth which gear at each revolution with the toothed part of said pinion, and having a non-toothed part which enters 95 said recesses, and a shaft upon which this pinion is keyed and which transmits the motion of the latter to the guiding-bar.

The foregoing specification of my improvements in mechanism for continuously and automatically feeding sheets of metal and other material to punching and like machines signed by me this 30th day of December, 1904.

ARTHUR WILZIN.
